[57] CLAIM

The ornamental design for a rotatable dispensing rack for food jars, substantially as shown and described.

DESCRIPTION

FIG. 1 is a top plan view of a rotatable dispensing rack for food jars showing my new design which is symmetrical about a central axis.

FIG. 2 is a front elevational view thereof, a portion being shown broken away for clarity;

FIG. 3 is a bottom plan view thereof; and

FIG. 4 is a horizontal sectional view taken in the plane indicated by the line 4—4 in FIG. 2, and illustrating the symmetry of the design about a central axis.

FIG. 1

FIG. 2

FIG. 3

FIG. 4
